UNITED STATES PATENT OFFICE

2,028,591

CHANGE RECEIVER AND ADVERTISING DEVICE

Leo Cohn, Los Angeles, Calif.

Application August 13, 1934, Serial No. 739,679

7 Claims. (Cl. 40—28)

This invention relates to change receivers and advertising devices, and an object is to provide a tilttable change tray which, as often as depressed by the hand when picking up coins deposited therein, will cause to be automatically actuated an advertising device having a display surface which will be conspicuously exhibited momentarily in front of the person operating the tray.

A further object is to provide an article of this character wherein the advertising device employed and also the tray are formed and constructed to automatically return to normal positions following each operation of depressing the tray.

Another object is to provide a device of this character consisting of but a few operative parts which are combined to produce a device the form of which is highly artistic.

A still further object is to provide a device of this character which is of light weight and portable, so that it can be readily placed wherever desired, such as upon show cases, counters or upon the customary front ledge of a cashier's booth.

With the above and other objects in view, which will appear as the nature of the invention is better understood, the same consists in the improved construction and novel arrangements of parts which will hereinafter be fully described and particularly pointed out in the claims.

In the accompanying drawing has been illustrated certain preferred forms of the invention, it being, however, understood that no limitations are necessarily made to the precise structural details therein exhibited, but that changes, alterations and modifications within the scope of the claims may be resorted to when desired.

In the accompanying drawing, Figure 1 is a plan view of the device with parts broken away;

Figure 2 is a view in front elevation thereof; Figure 3 is a section taken on the line 3—3 of Figure 1;

Figure 4 is a view similar to Figure 3, showing the position of the parts when the tray is manually depressed;

Figure 5 is a section on line 5—5 of Figure 3;

Figure 6 is a fragmentary view similar to Figure 4 of a slightly different form of the device.

In carrying the invention into practice, use is made of a suitable ornamental casing 10 having hollow vertical ends 11—11 and a horizontal supporting base 12.

Pivoted to tilt vertically on the hinge brackets

13 at the front of the base 12 is a change-receiving tray 14, the same dished as shown. This is best accomplished by upsetting the material of the tray to provide same with angularly related marginal beads 15. The tray is mounted slightly off center so as to normally assume the raised position shown in Figure 3.

Mounted to oscillate in bearing brackets 16 in the ends 11 of the casing is a shaft 17, the same passing longitudinally through a substantially rectangular display device 18, the same having an arcuate weight forming portion 19 concentrically related to the shaft 17 to maintain the device in the normal position shown in Figure 3. When in the position just referred to, the wall 20 of the device will rest against a stop pin 21 which rises vertically from the base 12, thus limiting the movement of the device in one direction about its axes. Movement of the device in an opposite direction will be limited by the angular surface 22 thereof contacting with said stop pin as shown in Figure 4.

The tray 14 is provided with a rearwardly extending arm 23 which is co-operable with a vertically movable pin 24, the latter having its ends mounted in the vertically aligned passages 25 in the bracket 16 at one end of the casing 10. The lower end of this pin is disposed above the nose 26 of the arm 23, so as to engage therewith when the tray is depressed manually to the position shown in Figure 4.

It should be borne in mind that the device 18 is fixed to rotate with the shaft 17 so that when the shaft is turned in the direction of the arrow in Figure 4 the device 18 will be made to assume a position where the curved display surface 27 of the weight portion 19 will be effectively exposed from above the inner edge of the tray when the latter is fully depressed. On reference to Figure 3 it will be observed that the device 18 normally occupies a position where the display surface 27 of the weight portion 19 is concealed in back of said tray.

The aforementioned pin 24 is provided with a longitudinal series of spaced apart rings 28 adapted to intermesh with the teeth of a small gear pinion 29 on shaft 17.

In the modified form of the invention shown in Figure 6 of the drawing, the gear pinion 29a of the device 18a meshes with the teeth 30 of a quadrant 31, the latter pivoted at 32 to a bracket 33. Said quadrant is provided with a pin 34 against which a co-acting pin 35 on a vertically movable stem 36 is adapted to engage. The stem is movable vertically in a fixed sleeve 55

31, and, as illustrated, an angular shaped portion 38 of the stem passes through an opening 25a in the bracket 16a, whereby to hold the stem against rotation. In this form, the arm 5 23a of the tray 14a is disposed beneath the stem 36 so as to engage same as the tray is depressed, and thus raise same in order that motion will be imparted to the pinion 29a through the quadrant 31.

10 Any suitable advertising matter can be printed or otherwise suitably formed on the display surface 27. In like manner, advertising matter can be placed on the angular surfaces 39 and 40 of the device 18. When coins are placed in 15 the tray, it follows that they will move downwardly therein and against the linear bead 15 at the front of the tray. As they are being gathered or picked up therefrom, the tray will be tilted to the position shown in Figure 4, causing 20 the advertising device 18 to turn on its axis until the surface 22 contacts with the pin, at which time said surface will be directly exhibited in an attractive manner in front of the person operating said tray. When pressure of 25 the hand is removed from the tray, the latter, as well as the device 18, will instantly return to its normal position, shown in Figure 3.

What is claimed is:

1. In mechanism of the class described, a 30 tiltable normally counter-balanced change tray; a tiltable display device having a display surface correlated to the change tray to be concealed thereby when the tray is in a normal counter-balanced position, and means for tilting the display device to expose the display surface thereof when the tray is depressed, and including a shaft supporting the display device; an arm on the tray; and means disposed to be engaged by the arm when the tray is depressed 35 and having operative motion imparting connection with the shaft to turn same and thus tilt the display device and expose the display surface thereof from the tray.

2. In mechanism of the class described, a 40 tiltable normally counter-balanced change tray; a tiltable display device having a display surface correlated to the change tray to be concealed in back thereof when the tray is in a normal counter-balanced position, means for tilting the display device to expose the display surface thereof when the tray is depressed, said means including an oscillatory shaft on which the display device is fixedly mounted to oscillate therewith, means on the tray, power transferring means cooperable with the tray means and the shaft to turn same in one direction, and a weight 45 portion on the display device for turning the shaft in an opposite direction.

3. In mechanism of the class described, a display device mounted to turn about a horizontal axis, a tiltable change tray disposed in front of the display device, the display device having a display surface normally concealed by the 5 tray, and means controlled by an actuation imparted to the tray when removing change therefrom for moving the display device to expose the display surface thereof.

4. In mechanism of the class described, a 10 display device mounted to turn about a supporting axis, weight means for moving the device in one direction, a tiltable change tray behind which a portion of the display device is concealed, and means co-operable with the 15 tray and said display device for moving the latter in an opposite direction on depressing the tray.

5. In combination with a tiltable change tray, 20 an advertising device movable about a horizontal axis and correlated with the tray to be concealed thereby when the tray is in one position, and means for moving the display device during movement of the tray to another position and exposing the device for view, and comprising a 25 gear pinion on the device; an arm fixed to the tray, and motion imparting means disposed to be engaged by the arm when the tray is tilted in one direction and having means co-operable with the pinion to turn the device about its 30 axis.

6. The combination, with a change tray pivoted 35 to tilt about a horizontal axis and having its pivot disposed to normally counterbalance the tray; an oscillatory display device mounted in back of the tray to be normally partly concealed by the tray and having a fixed pinion at its oscillatory axis; a vertically slidable device having a vertical series of rings adapted to mesh with the teeth of the pinion, and means on the tray for 40 moving the slidable device in one direction to turn the display device and display the normally concealed part thereof when the tray is tilted in one direction.

7. In mechanism of the class described, an 45 elongated display device mounted to turn about a horizontal axis and provided with a portion acting as a weight to turn the device in one direction; a vertically tiltable normally counter- 50 balanced change tray behind which a portion of the device is normally concealed; and means actuated by the tray for turning the device against the normal action of the weight portion thereof and thus display the normally concealed 55 portion of said device.
